COMBINED CURBSIDE LAMP AND METER PEDESTAL

Louis A. Hinz, 1731 Jewel Drive,
Longmont, Colo. 80501

Filed May 17, 1967, Ser. No. 7,168

Term of patent 14 years

(Cl. D48—20)

FIG. 1 is a perspective view of a combined lamp and meter pedestal showing my new design;

FIG. 2 is a front view;

FIG. 3 is a left side elevational view;

FIG. 4 is a rear view; and

FIG. 5 is a sectional view taken generally along the line 5—5 of FIG. 4 in the direction of the arrows.

I claim:

The ornamental design for a combined curbside lamp and meter pedestal, as shown and described.
